UNITED STATES PATENT OFFICE.

WILHELM SCHALLER, OF WIESBADEN, GERMANY.

SAFE-KEEPING DEVICE FOR WEARING-APPAREL.

SPECIFICATION forming part of Letters Patent No. 678,694, dated July 16, 1901.

Application filed October 1, 1900. Serial No. 31,623. (No model.)

To all whom it may concern:

Be it known that I, WILHELM SCHALLER, a subject of the Emperor of Germany, residing at the city of Wiesbaden, Empire of Germany, 5 have invented a new and useful Improved Safe-Keeping Device for Wearing-Apparel, of which the following is a specification.

My invention relates to devices for locking wearing-apparel when not in use to clothes-racks, &c., to prevent the easy appropriation by others of such articles.

The device is especially useful in hotels, clothes-rooms of meeting-halls, bath-houses, &c.

15 My invention will be more fully understood taken in connection with the accompanying drawings, forming part hereof, and in which—

Figure 1 is a front elevation of the device, showing the housing, the key, and the opening for inserting a shouldered stud. Fig. 2 is a section through the device, showing the mechanism and key in position when the device is not in use. Fig. 3 is a section through the device, showing the mechanism and key 25 in position when the shouldered stud is released from the device. Fig. 4 is a similar section showing the mechanism in position when the shouldered stud is inserted while the key is removed. Figs. 5, 6, and 7 are sections on the lines 5 5, 6 6, and 7 7 of Figs. 2, 3, and 4, respectively; and Fig. 8 shows in elevation and plan a shouldered stud adapted to be sewed onto a garment.

Referring now to the drawings for a further description of my invention, A is a housing, composed of a back plate *a* and a box *a'*, removably fastened to the back plate *a* by any suitable means. This housing may be fastened to a wall, closet, or clothes-rack by 35 screws *a*², or any other preferred fastening may be used. On the back plate *a* stubs *b* are provided to allow two clamping-cheeks *b'* and *b*² to slide in proper direction. These clamping-cheeks are bent at *b*³ and *b*⁴, so as 40 to lie close to the front plate of the box *a'*, and are cut out and beveled at *b*⁵ to permit a stud *s*, sewed or otherwise fastened to a garment, to be easily inserted. A stud *k* for the hollow key *k'* is secured to the back plate *a*,

serving to guide the key, and *r* is a bent plate 50 partly cut and secured also to the back plate *a* for the purpose of retaining the key when turned. In the shank of the key is cut a groove *k*², into which a plate *k*³, secured to a lever *e*, may enter in order to lock the key in 55 the device, as will be more fully described. The lever *e* is pivoted to the back plate *a* and hinged at *e*' to the clamping-cheek *b'*, the upper end of this lever *e* being adapted to be engaged by the beard *k*⁴ of the key *k'*. The 60 clamping-cheek *b'* is provided with an extension *b*⁶, with which the beard *k*⁴ of the key *k'* may come into contact. A spring *p* is provided for each of the clamping-cheeks *b'* and *b*² to force the bent portions *b*³ and *b*⁴ toward 65 each other.

The operation and use of the device are as follows: A garment being provided with a shouldered stud *s*, as shown in Figs. 7 and 8, may be secured to the device by inserting a 70 stud in the opening *a*³ of the box *a'*. This will force the clamping-cheeks *b'* and *b*² against the pressure of the springs *p* apart, and the portions *b*³ and *b*⁴ engage the thin portion of the stud *s*, holding the latter firmly in 75 place. (See Fig. 4.) In this position the plate *k*³ disengages the groove *k*² of the key *k'* and the latter may be withdrawn from the device.

If the garment is to be taken from the device, the key is inserted in the keyhole and 80 turned, the beard *k*⁴ engaging the extension *b*⁶ and the upper part of the lever *e*, Fig. 3, forcing the clamping-cheeks apart, so that the stud *s* or garment may be withdrawn. The cheeks *b'* and *b*², through the pressure of 85 the springs *p*, will then assume the position shown in Figs. 1 and 2, and the plate *k*³ will engage the groove *k*² of the key *k'*, which may be turned, but cannot be withdrawn from the device. 90

Having thus described the nature and objects of my invention, what I claim as new, and desire to secure by Letters Patent, is—

A device for the purposes specified, comprising a housing, two clamping-cheeks, springs 95 therefor, a key for operating said cheeks, a lever hinged to one of said cheeks and pivoted to said housing, a groove in said key, a

plate on said lever adapted to enter said groove when the cheeks are closed and to withdraw from the groove when the cheeks are separated, in combination with a shouldered stud, substantially as and for the purposes set forth.

In witness whereof I have hereunto set my

hand in the presence of two subscribing witnesses.

WILHELM SCHALLER.
